UNITED STATES PATENT OFFICE.

FRANK ZOUFAL, OF CICERO, ILLINOIS, ASSIGNOR OF ONE-HALF TO WILLIAM P. PONDELICEK, OF BERWYN, ILLINOIS.

HINGE.

Application filed April 16, 1926. Serial No. 102,499.

My invention relates to improvements in hinges, and especially those used in connection with screen or storm doors, and it consists in the combinations, constructions, and 5 arrangements herein described and claimed.

An object of my invention is to provide a hinge, the use of which will enable one to instantly attach a door to the casing, without the necessity of the use of tools of any 10 kind.

A further object of my invention is to provide a hinge which will permit the instant removal of a door or window.

A further object of my invention is to 15 provide a hinge which has all of the advantages of the ordinary hinge, in that it may be used in precisely the same manner as the ordinary hinge.

A further object of my invention is to 20 provide a hinge which will permit the door or window to be attached to the frame or casing at either side thereof by merely reversing the position of the hinge.

Other objects and advantages will appear 25 in the following specification, and the novel features of the invention will be particularly pointed out in the appended claim.

My invention is illustrated in the accompanying drawings, forming part of this application, in which

Figure 1 is a face view of one embodiment of my invention as applied to a door and frame,

Figure 2 is a section along the line 2—2 of Figure 1, and

Figure 3 is a face view of a modified form of the device.

In carrying out my invention, I make use of a hinge somewhat similar to the ordinary butt hinge. This has a portion 1 which is pivoted to a similar portion 2 by means of a pintle 3. Screw holes 4 are provided. In the member 2, I provide a slot 5 disposed between the screw holes 4 and in axial alignment therewith. Communicating with the slot 5 is a lateral slot 6 which preferably flares outwardly to provide beveled edges 7.

The member 1 also has a slot or opening 8 in alignment with the screw openings 4. It 5 will be observed that both the slots 5 and 8 extend above and below the central portion of the hinge to equal distances.

From the foregoing description of the various parts of the device, the operation 55 thereof may be readily understood. In Fig-

ure 1, I have shown a portion of a door, or window, or other member, which it is desired to hinge, this member being designated as 10. The casing or frame is shown at 9. The hinge is secured to the door by means 60 of screws 11 in the ordinary manner.

To the casing, I secure a retaining member 12 which may be a screw, a nail, or a similar member having a head portion larger than the slot 5. This retaining member 65 is located at such a distance from the top or the bottom of the door as to bring the door in the proper position when the body portion of the retaining member 12 is at the proper extremity of the slot 5. 70

The door or window has of course hinges at the upper and lower portions. Now when it is desired to remove the door, all that is necessary is to raise it until the body portion 12' of the screw or retaining member 12 75 is in registration with the transverse slot 6, when the door may be pulled outwardly free from the casing. In hanging the door, the latter is pushed toward the retaining member which is guided by the beveled edges 7 80 into the slot 6, and thence into the slot 5, when the door may be lowered to rest on the body portion 12', the head portion of the screw 12 holding the door firmly in position. 85

In Figure 3, I have shown a modified form of the device in which the hinge member 2' has upper and lower inclined slots 13 and 14, respectively. In this form of the device, the retaining member 15 is designed to enter the lower slot 14, so that when the door is lowered, the hinge member will pass over the body portion of the retaining member and will draw the door into position. 90 In this form of the device, in order to remove the door, it is pulled upwardly, when 95 the hinge member will pass off from the retaining member.

The purpose of the slot 8 in the member 1 in both figures is to provide room for the head of the retaining member 12. In Figure 2, I have shown a recess 15 in the casing 9. Ordinarily, however, it is not necessary to make this recess, since the provision of the slot 8 alone gives room for the head of the screw 12, and even if it should strike the 100 casing, it will make a recess therein which will permit the door to close to its proper position in most cases. It is desirable of course to have the door closed, and in some instances it may be advisable to make the 105 110

recess 15 in the casing, but ordinarily it is not.

In both forms of the device, the operation of putting on or taking off the door may 5 be done almost instantly and this obviates the necessity of removing any screws or using any tools in the act of putting the door on or off. As stated above, the hinge may 10 be used in the ordinary manner, since if it is desired to make a permanent connection, the screw holes may be used.

I claim:

A hinge comprising a pair of hinge members, each of said members having a pair of 15 aligned screw openings, one of said members

having a slot in alignment with certain of said screw openings and extending above and below the central portion of the member, a second slot communicating with said first named slot and extending to the edge 20 of the member, the outer portions of the slot being flared to provide a guide edge, the companion hinge member having a slot extending above and below the central portion of the hinge to equal distances, and being 25 arranged to receive the head of a retaining member when the latter is in either end of the first named slot of the other hinge member.

FRANK ZOUFAL.
